UNITED STATES PATENT OFFICE.

WILLIAM DIEMER, OF TOLEDO, OHIO, ASSIGNOR TO GENDRON WHEEL COMPANY, OF TOLEDO, OHIO, A CORPORATION OF OHIO.

COUCH.

967,890.

Specification of Letters Patent. Patented Aug. 23, 1910.

Application filed March 13, 1909. Serial No. 483,261.

To all whom it may concern:

Be it known that I, WILLIAM DIEMER, a citizen of the United States of America, residing at Toledo, in the county of Lucas and State of Ohio, have invented certain new and useful Improvements in Couches, of which the following is a specification, reference being had therein to the accompanying drawings.

10 This invention relates to new and useful improvements in couches and consists particularly in the construction of a couch with a support by which it may be suspended to swing, and provided with legs which may be 15 moved to support the couch upon the floor in the usual manner when it is not desired to be used as a swing; and it is also preferably provided with a hinged back so that the back may be inclined at varying angles; 20 and also, when desired for shipping and storage purposes, the couch may be adjusted into a very compact space.

The invention further consists in the construction and arrangement in combination 25 of the various parts, as will be fully herein-after described and particularly pointed out in the claims.

In the drawings,—Figure 1 is a perspective view of my improved couch, with parts 30 of the seat and back broken away at one point to more clearly illustrate the construction; and Fig. 2 is a vertical cross-sectional view therethrough, near one of the legs.

A represents the couch frame, which I 35 have shown as consisting of two side-bars connected by suitable cross-bars B, and this frame may be covered with canvas or other cover C. At each end of the frame and preferably between the side-bars thereof, I 40 hinge the frames D at their lower ends, which form head-rests. These head-rests are preferably adjustable to any desired angle, or they may be moved into practically the same plane as the body of the couch. This 45 adjustment may be effected in any desired manner; I have shown it effected by means of the rod *a* on the head-rests engaging the spring-clamp *b* on the side-bar *c*.

To the underside of the frame are hinged 50 leg frames F, which I have shown as hinged to brackets *d*. These leg frames are provided with braces G which have a rule-joint *e*, so that when desired the legs may be folded up parallel with and on the underside 55 of the couch-frame.

At the rear side of the frame near each end I have provided brackets H to which is pivoted the back I. This is made of a suitable frame-work and is steadied and adjusted by means of the stay-bars J pivoted 60 at their upper end to the I-bolt K passing through one of the members of the back-frame and at the lower end provided with a bolt *h* passing through a slot *i* in the up-standing portion *k* of a rearwardly-extending 65 bracket L secured to the rear side-bar of the frame. The bolt *h* is provided with a clamping-nut *l* so that the back may be adjusted at any desired angle to the seat or body of the couch. When it is desired to 70 fold the back down, the nut *l* may be removed and the back turned upon its pivot *m* into the position shown in dotted lines in Fig. 2. The brace J may be folded against the back-frame parallel with the vertical 75 members thereof, or it may be turned at any desired angle to said members, by means of the swivel bolt *k*.

At the ends of the side-bars I provide the brackets *o*; preferably having hooks *r* with 80 which the suspension chains *s* engage, these suspension chains passing up beside the head-rests and coming to a common point of support above, so that they may be suspended from a single hook in the ceiling of 85 the porch and the couch thus be swung either front and back or end-wise. The suspension chains or devices *s* being arranged outside of the head-rests, the head-rests may be adjusted between them to any desired angle 90 and the occupant of the couch, by reaching up, can take hold of the cross spreader-bar *t* and cause the couch to swing while lying thereon. This spreader-bar also keeps the chains free from contact with the sides of 95 the head-rests, even when the same is adjusted in its lower positions.

What I claim as my invention is:

1. The combination of a couch frame, hinged head-rests thereon, means connected 100 to said frame for adjusting said head-rests, brackets carried by said frame, a back hinged to said brackets, a bracket extending rearward from said frame, a brace rod having its opposite ends respectively engaging the back and said bracket, one of the rod ends having an adjustable engagement with the member it engages. 105

2. The combination with a couch frame, hinged head-rests thereon, means connected 110

to said frame for adjusting said head-rests, brackets carried by said frame, a back hinged to said brackets, brackets extending rearwardly from said frame, brace rods having their opposite ends respectively pivoted to the back and adjustably engaging the brackets, the engagement of said rods with their respective brackets being such as to permit the detachment of the former from the latter.

3. The combination with a couch frame including spaced side bars, a seat carried by said side bars, the ends of the latter projecting beyond the seat, head-rests pivoted to the extensions of said side bars adjacent the ends of the seat, swinging supports secured to the ends of the side bars and between which the head-rests may move, and means independent of the swinging supports for adjusting one of said head rests.

4. The combination with a couch frame

including spaced side bars, a seat carried by said side bars, the ends of the latter projecting beyond the seat, head-rests pivoted to the extensions of said side bars adjacent the ends of the seat, swinging supports secured to the projecting ends of the side bars, the supports at each end of the couch frame being spaced sufficiently to permit the head-rests to move therebetween, and means independent of the supports for independently adjusting said head-rests, comprising a rod secured to the head-rest, and a locking clip carried by the side bars engaging the rod and adapted to hold the latter in its different positions of adjustment.

In testimony whereof I affix my signature in presence of two witnesses.

WILLIAM DIEMER.
